UNITED STATES PATENT OFFICE

92,900

DESIGN FOR A MODERNISTIC VIOLIN

Alfred Grosjean, Pasadena, Calif., assignor of one-half to Edna Dundon, Altadena, Calif.

Application May 7, 1934, Serial No. 51,709

Term of patent 14 years

To all whom it may concern:

Be it known that I, ALFRED GROSJEAN, a citizen of the United States and residing at Pasadena, in the county of Los Angeles and State of California, have invented a new, original, and ornamental Design for a Modernistic Violin, of which the following is a specification, reference being had to the accompanying drawing forming a part thereof.

In the accompanying drawing Fig. 1 is a top plan view of the article showing my new design:

Fig. 2 is a side elevational view, being broken away at the upper portion for convenience of illustration;

Fig. 3 is a cross-sectional view taken on line 3—3 of Fig. 2.

I claim:

The ornamental design for a modernistic violin as shown and described.

ALFRED GROSJEAN.
